UNITED STATES PATENT OFFICE.

WELLS HENDERSHOTT, OF BATAVIA, NEW YORK.

IMPROVEMENT IN RAILROAD-CHAIRS.

Specification forming part of Letters Patent No. 42,480, dated April 26, 1864.

To all whom it may concern:

Be it known that I, WELLS HENDERSHOTT, of the town of Batavia, in the county of Genesee and State of New York, have invented a new and Improved Self-Adjusting Rail Chair and Coupling for Railroads; and I do hereby declare that the following is a full and exact description thereof, reference being had to the accompanying drawings, and to the letters of reference marked thereon.

The nature of my invention consists in making a rail chair and coupling for the ends or joints of rails on railroads, which will preserve an even running-surface for trains of cars, will allow the expansion and contraction of the rails by heat and cold, will grasp and hold the rails fast without bolts by the pressure of the weight of passing trains of cars, and partially release them from said grasp as soon as the weight is removed, thereby lessening the force of any blows of passing trains upon the ends of the rails.

To enable others skilled in the art to make and use my invention, I will proceed to describe its construction and operation.

In the drawings, Figure 1 is an end sectional view of the chair and coupling with the ends of two rails without any weight thereon. Fig. 2 is a longitudinal sectional view. Fig. 3 represents a supporter placed in the middle of the rail and bolted thereto, and Fig. 4 is an end sectional view of the chair and rail when the weight of passing trains is resting thereon.

I make an open box, with the sides and ends about one half inch higher than the bottom, of cast or wrought iron, about one half of an inch thick, about one foot long, and from six to eight inches wide. The bottom, on its upper surface, inclines from the sides toward the center, so that the center is only about one half of the thickness of the sides, and about in the center of the bottom is an opening, which may be about one inch square, or it may be made much larger. This box is distinguished on the drawings by the letters *a a*, the inclined planes by the letters *b b*, and the opening by the letter *c*. Inside of this box, and fitting therein, I place a chair and coupling, in which rest the ends of the rails, is made in two parts, of cast or wrought iron, and under the rail, in the center thereof, is connected by means of a hinge, as shown at

g, and these two parts are designated by the letters *e e*, and are provided with projections or lugs *d d*, which are fitted loosely into the opening *c* in the bottom of the box. The chair is made in the shape of the rail; but without any pressure thereon there is a small space left between the rail and chair, and from the hinge each way the bottom of the inside of the chair descends and forms two inclined planes, so that when the pressure of a train of cars rests upon the rails the hinged part is pressed down and the projections open slightly, and the bottom of the chair rests partly upon the two inclined planes in the bottom of the box, and the bottom of the rail rests partly upon the two inclined planes on the inside of the chair, forming a strong support, and the sides of the chair press against and support the rails. When the weight of passing trains is removed, the grip or grasp upon the rails is relaxed, and there is not such a confinement as to prevent expansion and contraction. The chair is also supported by the flanges on the sides of the box, as shown at *h h*. The rails are made alike, both at the top and bottom, and may be turned when one side is worn or injured; but my invention is equally adapted for any kind of rail. The two planes on the inside of the chair are designated by letters *f f*, and the two planes upon the bottom of the box are designated by the letters *b b*.

By my arrangement it is apparent that the chair and rail are securely held either without the pressure of passing trains or with it, and that a train passing over the rails will receive a much less shock than when the rails and chairs are firmly bolted, as there is a little give as the trains pass over each chair. As an additional security for holding the rails, I attach at about the middle of each rail a supporter, Fig. 3, which is bolted to the rail and will allow it to expand and contract either way. This supporter is a narrow chair about two inches wide, fitted and bolted to the rail, and also bolted to the cross-tie, and has similar projections through the shoe to those upon the large chair; but I do not claim bolting this supporter to the rail.

Having thus described my invention and its construction, what I claim, and desire to secure by Letters Patent, is—

1. Making a rail chair and coupling for rail-

roads, connected by a hinge or hinges at the bottom with the inclined planes *b b* and *ff*, so that the pressure and weight of the cars will firmly hold the rails, and when the weight is removed the hold will be relaxed and allow the rails to expand and contract, for the purposes described, and in the manner as substantially set forth.

2. The inclined planes, in combination with the hinge, for the purposes described, and as set forth.

3. The hinge connecting the two parts of the chair and coupling, for the purposes described, and substantially as set forth.

4. The inclined planes, for the purposes described, and as set forth.

5. In combination with said rail chair and

coupling, a rail that may be turned over, with both the top and bottom sides alike.

6. In combination with said rail chair and coupling, the supporter for the middle of the rail, constructed in the manner and for the purposes described.

7. The projections *d d*, extending below the chair into the opening *c* in the bottom of the box, upon which the chair rests, for the purposes described, and substantially as set forth.

8. The box *a a*, in which the chair or coupling is placed, for the purposes described, and substantially as set forth.

WELLS HENDERSON.
